Patented Mar. 21, 1916.

UNITED STATES PATENT OFFICE.

THEODORE H. MILLINGTON, OF MINNEAPOLIS, MINNESOTA, ASSIGNOR TO JAMES A. CAMERON, OF CHICAGO, ILLINOIS.

CAB BLOCK-SIGNALING SYSTEM.

1,176,234.

Specification of Letters Patent. Patented Mar. 21, 1916.

Continuation of application Serial No. 460,805, filed November 3, 1908. This application filed October 31, 1910. Serial No. 590,082.

To all whom it may concern:

Be it known that I, THEODORE H. MILLINGTON, a citizen of the United States of America, and a resident of Minneapolis, county of 5 Hennepin, State of Minnesota, have invented certain new and useful Improvements in Cab Block-Signaling Systems, of which the following is a specification.

My invention relates to certain new and 10 useful improvements in electric signaling systems, and a specific embodiment thereof is shown in the accompanying drawing, which is a diagrammatic view showing, in the upper part, the track system and in the 15 lower part the arrangement of the parts carried by the cab of the engine, which is to receive the signal.

Referring to the drawing, A¹, A¹, A², B² and A³, B³ are the rails of blocks which are 20 marked on the drawing Block 1, Block 2 and Block 3, and will be so referred to. The rails of the respective blocks are insulated from each other in the usual way and the two rails of each block are connected to the 25 terminals of batteries, one for each block. The rails of each block are connected respectively to the terminals of relays C¹, C² in the corresponding blocks, each of the said relays being adapted, when its armature is 30 attracted, to close local circuits c¹, c² in which are magnets D¹, D², and suitable means for supplying electric current, the same being shown in the form of batteries. When there is no train upon any given 35 block, the current from the battery attached to the rails thereof flows through the corresponding relay closing the circuit c¹ or c² as the case may be and thereby energizing the magnet D¹ or D². When a train is in any 40 given block, it short-circuits the battery between the rails thereof as shown in block 2, thereby depriving the corresponding relay of current and thus breaking the circuit c¹ or c² as the case may be and deenergizing 45 the magnet D¹ or D². In the drawing, block 1 is shown clear and block 2 with a train in place and the resulting positions of the relays and magnets with their armatures is plainly illustrated.

50 Generators of Hertzian waves or other suitable means for transmitting electrical influences through space are provided as shown at E¹, E²; one such generator may be supplied for each block. To one side of

the track, and extending substantially the 55 length of each block is a wave-wire, the same being indicated in the drawing by the wires F¹, F², and on the opposite side of the track and near the end of the block in the direction in which the train is moving are 60 shorter wave-wires, which are indicated in the drawing by the wires G¹ and G². The armatures of the magnet D¹, D² heretofore described, are provided with contacts whereby when the magnets are energized, the 65 wave-wires in the next block in the direction from which the trains move are connected with the generators so that said wave-wires are supplied with the necessary oscillations or influences to operate the cab-signaling device presently to be described. The electrical influences are made of such strength that each wave-wire will operate only within a comparatively small zone. The wave 70 wire F¹, for instance, affecting a zone which does not overlap the zone actuated by the wave-wire G¹. It is found as a matter of practice that the various wave-wires can be placed in such positions that this can readily be accomplished.

The result of the foregoing construction is 75 obviously that when the train is in block 2, the wave-wire F¹ and the wave-wire G¹ will be deenergized, while the corresponding wires F² and G² will be supplied with energy. Thus the absence of energy in any given block on the wave-wire thereof will 80 indicate a train in the next preceding block, or a condition of danger, while the presence of such electrical influences or energy will 85 generally indicate safety.

I am aware that it has been heretofore proposed to utilize electrical waves for the purpose of conveying train-signals through wave-wires strung beside the track, but the 90 objection to such a system has been that there was no danger indicated in the same block in which a train was located. Thus a train depending solely upon the presence or absence of electrical energy in the wave-wires would, after running under control 95 through block 1, get a signal indicating safety when it entered block 2, and were the train in block 2 wrecked, the engineer following, receiving a safety signal would suppose that the train had passed out of the 100 block and would proceed at full speed, where the condition in fact was one of the great-

100

105

est danger. The purpose of the present invention is to provide means whereby under such conditions the train will still continue to receive a signal of danger even though 5 entering a block in which the presence of waves in the wave-wire would normally indicate safety.

The detector or receiving device H is in the cab and is provided with a receiving 10 antenna R so arranged as to be affected only by the main transmitting antennae F¹, F². This detector controls the circuit through a magnet or solenoid H¹, the armature h of which is pivotally secured to a lever H² pivoted at h¹ and having at its opposite end a cam-portion h² terminating in a shoulder h³. In certain cases it may be possible to place the detector H directly in series with the magnet H¹, but in practice a relay will 15 probably be interposed for obvious reasons. A second detector I is provided with a receiving antenna R¹ so arranged as to be affected only by the energy emanating from the wave-wires G¹, G², and it controls the 20 circuit through a magnet I¹, having a pivoted armature i, on the upper end of which is a catch or shoulder i¹ to engage with the shoulder h³ on the lever H².

The operation of the cab portion of the 30 device will now be readily apparent. As long as there is oscillation in the wave-wire F¹, the circuit through the coherer H will be closed, the armature h of the solenoid H¹ will be held in its upward position and 35 the lever H² will be held thereby in such position as to hold the indicating apparatus at safety. The indicating apparatus may be of any desired form controlled by the lever H². If desired, the lever H² may 40 control a whistle or a visual signal or may control the air-brake and throttle in any way well known in the art whereby such results may be automatically accomplished. The moment the train enters a block where the 45 wave-wire is not energized, that is, a block where there is a train in the preceding block, the detector will break the circuit through the solenoid H¹, permitting the armature thereof to drop and rocking the lever H² 50 about its pivot. The right hand end of said lever will rise, the shoulder h³ being engaged by the catch on the armature i of the magnet I¹ in the manner illustrated in the drawing. The cab-indicator will continue to 55 indicate danger and the engineer will run the train under control. Should the danger signal be set in block 1 (as it would be on a train entering the block as indicated in Fig. 1), when the train enters block 2 in 60 which there already is another train (as illustrated) the circuit will again be re-established through the solenoid H¹, but the engagement of the armature i will hold the indicating mechanism in position where it 65 shows danger. If, however, the preceding

train has cleared block 2 before the following train reached the entrance of said block the waves thrown out by the unlock wave-wire G¹ would affect the detector I, thereby energizing the magnet I¹ and withdrawing 70 the armature i and its catch from engagement with the lever h², whereupon the circuit passing through the solenoid H¹ would set the device at safety. It will thus be seen that the operation of my device is to 75 keep at danger position the cab-device when a train enters a block which is succeeded by a block in which a train or engine is located. The device is automatically held at danger and remains so under all conditions, so that 80 the engine must proceed under control until a block is reached which is followed by an empty block, in which case, and in which case only, the device returns to safety. The construction of the apparatus to carry out 85 this result may be very largely varied. I consider it of the greatest importance to provide locking or equivalent means for placing and keeping the device at danger, preventing it from returning to safety upon 90 entering a block already occupied by a train. As far as I am aware prior systems were faulty in that they did not give accurate 95 information to a following train entering a block already occupied. When the danger device is once set in danger position it may be returned to safety in various ways.

I realize that considerable variation is possible in the details of construction shown without departing from the spirit of my invention, and I do not intend therefore, to limit myself to the specific form herein 100 shown and described.

I claim:

1. In a cab signaling system, a track divided into blocks, means to transmit through space electrical influences indicating the conditions in a block ahead, signaling means on the cab normally within said field of influence indicative of the condition of the block ahead, and responsive to variation of said influences to indicate danger or safety ahead, means for holding the signaling means in danger position when danger is once indicated, regardless of the restoration 105 of said influences to safety indicating conditions; and means local to a predetermined extent of the block for releasing said holding means when said influences indicate safety in the block ahead.

2. In a cab signaling system, a signal device, means for producing a safety indication thereof, means for setting the signal device in danger indication when the engine enters a block behind an occupied block, means for holding the signal device in danger position, means for automatically releasing said holding means, and separate means associated with the track for controlling said release means.

3. A cab signaling system, including a wave wire along the track and a device which indicates safety and danger, means for automatically setting the device at danger when the train enters a block wherein there are no electrical influences produced in the wave wire, means for maintaining the device in the danger position, and a controlling device at the end of the block for said maintaining means held from operation by the presence of a train in the next block, whereby the signal device will remain at danger when the engine enters a block already occupied by another train.
4. A cab signaling system, including means along the track for transmitting electrical influences through space and a device on the train which indicates a condition of safety when it receives influences emanating from said transmitting means and danger in the absence of such influences, means for maintaining said train device in the danger position, and means for automatically releasing said maintaining means to permit said train device to return to its safety indication only when the train enters an unoccupied block which is succeeded by another unoccupied block.
5. A cab signaling system, including means along the track for transmitting electrical influences through space and a device on the train which indicates a condition of safety when it receives influences emanating from said transmitting means and danger in the absence of such influences, means for maintaining said signal device at danger indication when so set, additional means in each block for transmitting electrical influences through space, and means on the train affected only by said additional transmitting means and adapted to release said train device from said danger indication.
6. A cab signaling system, including means along the track for transmitting electrical influences through space and a device on the train which indicates a condition of safety when it receives influences emanating from said transmitting means and danger in the absence of such influences, means for maintaining said signal device at danger indication when so set, additional means in each block for transmitting electrical influences through space, means on the train affected only by said additional transmitting means and adapted to release said train device from said danger indication, and a common source for supplying energy to both of said transmitting means.
7. In a cab signaling system, a signal device, means for setting said signal device at danger indication when the train is in any position in a block behind an occupied block, means for preventing said signal device from indicating safety when the engine enters an occupied block, and means for au-
- tomatically causing said signal device to indicate safety when at least one clear block precedes the engine.
8. In a block signaling system, generators of electrical influence, long and short transmitting antennæ connected with said generators, a device on the train controlled by influences from the longer antennæ and adapted to produce a certain signal indication, and means for maintaining said device at said certain indication and adapted to be released by influences emanating from the shorter antennæ.
9. In a block signaling system, a track divided into blocks, track circuits, means for transmitting electrical influences through space and comprising short and long transmitting antennæ, and a source of electrical energy for same, means controlled by said track circuits for energizing and deenergizing said antennæ, a device on the rolling stock adapted to be influenced by the longer transmitting antenna to indicate certain conditions, means for holding said device to continue such indication, and means adapted to be influenced by the shorter transmitting antenna for releasing said holding means.
10. A block signaling system, comprising a track divided into blocks, track circuits, means controlled by said track circuits for transmitting electrical influences through space within the field of said blocks, a device on the rolling stock for indicating the presence or absence of such electrical influences, and means controlled by conditions of danger for preventing said device from indicating the presence of said electrical influences.
11. In a cab signaling system, a track system including a transmitting antenna, and means for energizing it, a device in the cab for indicating danger when said antenna is deenergized, and means for maintaining said device at the danger indication.
12. In a cab signaling system, a track system including a transmitting antenna, and means for energizing it, a device in the cab for indicating danger when said antenna is deenergized, means for maintaining said device at the danger indication, and automatic means for releasing said holding means.
13. In a cab signaling system, a track system including a transmitting antenna, and means for energizing it, a device in the cab for indicating danger when said antenna is deenergized, means for maintaining said device at the danger indication, and means for releasing said holding means.
14. In a cab signaling system, a track system including a transmitting antenna, and means for energizing it, a device in the cab for indicating danger when said antenna is deenergized, means for main-

taining said device at the danger indication, and means in the track system for causing the release of said maintaining means.

15. In a cab signaling system, a track system including an antenna for transmitting electrical influences through space, a device in the cab controlled by such influences for indicating conditions of safety and danger, means in the cab device for maintaining one of such indications irrespective of the continued transmission of influences from said antenna.

16. In a cab signaling system, a track system including an antenna for transmitting electrical influences through space, a device in the cab controlled by such influences for indicating conditions of safety and danger, means in the cab device for maintaining one of such indications irrespective of the continued transmission of influences from said antenna.

17. In a cab signaling system, a track system including an antenna for transmitting electrical influences through space, a device in the cab controlled by such influences for indicating conditions of safety and danger, means in the cab device for maintaining one of such indications irrespective of the continued transmission of influences from said antenna, and means for releasing said maintaining means.

18. In a cab signaling system, a track system including an antenna for transmitting electrical influences through space, a device in the cab controlled by such influences for indicating conditions of safety and danger, means in the cab device for maintaining one of such indications irrespective of the continued transmission of influences from said antenna, a second transmitting antenna included in said track system and adapted to release said maintaining means.

19. In a cab signaling system, a track system including an antenna for transmitting electrical influences through space, a device in the cab controlled by such influences for indicating conditions of safety and danger, means in the cab device for maintaining one of such indications irrespective of the continued transmission of influences from said antenna, a second transmitting antenna included in said track system and adapted to release said maintaining means, and means influenced by the relation of the rolling stock to the track system for energizing said antennæ.

20. In a cab signaling system, a track system including an antenna for transmitting electrical influences through space, a device in the cab controlled by such influences for indicating conditions of safety and danger, means in the cab device for maintaining one of such indications irrespective of a change in the condition of said antenna, and means influenced by the relation of the rolling

stock to the track system for releasing said maintaining means.

21. In a cab signaling system, means to transmit through space electrical influences indicating the conditions in advance of the movement of the train, signaling means on a cab normally within said field of influence indicative of the condition of the track ahead and responsive to the variation of said influences to indicate danger or safety ahead, means for holding the signaling means in danger position when danger is once indicated, and means for releasing said holding means when said influences indicate safety ahead.

22. In a cab signaling system, means to transmit through space electrical influences indicating the conditions in advance of the movement of the train, signaling means on a cab normally within said field of influence indicative of the condition of the track ahead and responsive to the variation of said influences to indicate danger or safety ahead, means for holding the signaling means in danger position when danger is once indicated, regardless of the restoration of said influences to safety indicating condition; and means for releasing said holding means when said influences indicate safety ahead.

23. In a cab signaling system, means to transmit through space electrical influences indicating the conditions in advance of the movement of the train, signaling means on a cab normally within said field of influence indicative of the condition of the track ahead and responsive to the variation of said influences to indicate danger or safety ahead, means for holding the signaling means in danger position when danger is once indicated, regardless of the restoration of said influences to safety indicating condition; and means local to a predetermined extent of track for releasing said holding means when said influences indicate safety in the direction of the movement of the train.

24. In a cab signaling system, a track system including means along the railway for transmitting electrical influences and means for energizing it, a device in the cab for indicating danger when said first mentioned means is deenergized, and means for maintaining said device at the danger indication.

25. A cab signaling system, including means along the right of way for transmitting a pre-determined character of electrical influences, and means for energizing same, a device in a cab adapted to be controlled by said influences and to indicate danger when said influences cease and means for maintaining said danger indication irrespective of the return of said influences.

26. In a cab signaling system, the track divided into blocks, track circuits for said blocks, means running throughout the length of each of said blocks and adapted to emit

electrical influences, means running throughout only a portion of each of said blocks and adapted to emit electrical influences, means for generating said electrical influences, said 5 electrical influences being controlled by said track circuits, a cab device having a receiving device adapted to be controlled by the electrical influences from said first mentioned means, and having a separate receiving device adapted to be controlled by the 10 electrical influences from said second mentioned means, for the purpose described.

27. In a cab signaling system, the track divided into blocks, track circuits for said 15 blocks, means running throughout the length of said blocks and adapted to emit electrical

influences, means for generating said electrical influences, means running throughout only a portion of each of said blocks and adapted to emit electrical influences and connected to separate means for generating said electrical influences, said electrical influences being controlled by said tracks circuits, a cab device having a plurality of receiving devices adapted to be influenced by said electrical influences for the purpose described. 20 25

Signed at Chicago, this 28th day of October, 1910.
